CLAIM

The ornamental design for a driving recorder, as shown and described.

DESCRIPTION

FIG. 1 is a left, front, and bottom perspective view of a driving recorder;

FIG. 2 is a right, front, and top perspective view thereof;

FIG. 3 is front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines shown in the drawings illustrate portions of the driving recorder that form no part of the claimed design.
